DESIGN FOR A CLOSURE FOR A JAR OR SIMILAR ARTICLE

George M. Hood, Glendale, Calif.

Application October 12, 1945, Serial No. 122,792

Term of patent 3½ years

(Cl. D58—26)

To all whom it may concern:

Be it known that I, George M. Hood, a citizen of the United States, residing at Glendale, county of Los Angeles, and State of California, have invented a new, original, and ornamental Design for a Closure for a Jar or Similar Article, of which the following is a specification, reference being had to the accompanying drawing, forming part thereof.

The figure is a perspective view of a closure for a jar or similar article, showing my new design.

I claim:

The ornamental design for a closure for a jar or similar article, substantially as shown.

GEORGE M. HOOD,
